KITCHEN COUNTER STORAGE CABINET

Thomas L. Peckenpaugh, P.O. Box 533,
Cambria, Calif. 93428

Filed Apr. 20, 1972, Ser. No. 246,118

Term of patent 14 years

Int. Cl. D6—04

U.S. Cl. D6—167

FIG. 1

FIG. 2

FIG. 3

FIG. 4

FIG. 1 is a perspective view from the front and right of and slightly above my kitchen counter storage cabinet;

FIG. 2 is a perspective view showing the front and top access doors to the cabinet open showing a revolving compartmentalized spool assembly for storing kitchenware such as pots, pans and the like;

FIG. 3 is a rear elevation view of the kitchen counter storage cabinet illustrating the access doors in the rear of the cabinet; and

FIG. 4 is a view in rear elevation of the cabinet of FIG. 1 but wherein the back is a plain and unornamented surface.

I claim:

The ornamental design of the kitchen counter storage cabinet, substantially as shown and described.
